US00D737652S

(12) **United States Design Patent**
Harden et al.

(10) **Patent No.:** **US D737,652 S**
(45) **Date of Patent:** **** Sep. 1, 2015**

(54) **HANDLE**

(71) Applicant: **BOBRICK WASHROOM EQUIPMENT, INC.**, North Hollywood, CA (US)

(72) Inventors: **Daniel Kendall Harden**, Palo Alto, CA (US); **Elliot Lucas Ortiz**, San Francisco, CA (US); **Hirotomi Teranishi**, San Jose, CA (US)

(73) Assignee: **Bobrick Washroom Equipment, Inc.**, North Hollywood, CA (US)

(**) Term: **14 Years**

(21) Appl. No.: **29/481,874**

(22) Filed: **Feb. 11, 2014**

(51) LOC (10) Cl. **08-06**

(52) U.S. Cl.

USPC **D8/302**; D8/308

(57) **CLAIM**

The ornamental design for a handle, as shown and described.

DESCRIPTION

FIG. 1 is a perspective view of a handle according to a first embodiment;

FIG. 2 is a top view thereof;

FIG. 3 is a front view thereof;

FIG. 4 is a left side view thereof;

FIG. 5 is a right side view thereof;

FIG. 6 is a perspective view of a handle according to a second embodiment;

FIG. 7 is a top view thereof;

FIG. 8 is a front view thereof;

FIG. 9 is a left side view thereof; and,

FIG. 10 is a right side view thereof.

The broken lines shown represent unclaimed subject matter and form part of the claimed design.

1 Claim, 8 Drawing Sheets
